C. H. SCHOFF.
DISTILLATE BURNER.
APPLICATION FILED MAR. 10, 1908.

922,522.

Patented May 25, 1909.

UNITED STATES PATENT OFFICE.

CHARLES H. SCHOFF, OF HALF MOON BAY, CALIFORNIA.

DISTILLATE-BURNER.

No. 922,522.

Specification of Letters Patent.

Patented May 25, 1909.

Application filed March 10, 1908. Serial No. 420,235.

To all whom it may concern:

Be it known that I, CHARLES H. SCHOFF, a citizen of the United States, residing at Half Moon Bay, in the county of San Mateo and State of California, have invented certain new and useful Improvements in Distillate-Burners, of which the following is a specification.

The present invention relates to improvements in liquid fuel burners of that type in which the fuel is vaporized and converted into a gas previous to combustion.

The object of the invention is to design a burner of this type which will operate without the usual roaring noise and which will evenly distribute the heat throughout the fire box.

The invention further contemplates a novel construction of burner tube which operates to strain the gas previous to ignition and to prevent any solid particles entering the jet opening of the burner.

For a full description of the invention and the merits thereof and also to acquire a knowledge of the details of construction and the means for effecting the result, reference is to be had to the following description and accompanying drawings, in which:

Figure 1 is a perspective view of a liquid fuel burner embodying the invention. Fig. 2 is a longitudinal sectional view through the same. Fig. 3 is a transverse sectional view. Fig. 4 is an enlarged sectional view through one of the burner tubes.

Corresponding and like parts are referred to in the following description and indicated in all the views of the drawings by the same reference characters.

Specifically describing the present embodiment of the invention, the numeral 1 designates the generator which has a tubular formation and is preferably arranged in a horizontal position. The opposite ends of the generator may be closed in any suitable manner as by means of the caps 2, one of which receives the supply pipe 3 through which oil or distillate passes to the generator, the flow of the oil being controlled by a valve 4 of any approved construction. One or more openings are formed in the bottom of the generator and threaded within these openings are the burner tubes 5, the openings through the burner tubes being contracted at their lower or outer ends to provide the jet openings 6. It will also be observed that the ends of the burner tubes projecting out-

wardly beyond the generator have an angular formation as indicated at 7 to admit of the burners being readily placed in position or removed therefrom by means of a wrench or similar tool. These burner tubes project within the generator and the upper extremities of the tubes are shown as abutting against the top of the generator by means of which they are closed. Lateral openings 8 are formed in the upper portion of the burner tubes 5 through which the gas enters the tubes previous to being discharged through the jet openings 6. These lateral openings 8 serve to strain the gas and exclude any solid particles which might lodge in the jet openings and interfere with the proper operation of the burner.

Located immediately below the generator 1 is a flame deflector 9 which serves to divide the flame and deflect the same laterally in opposite directions. As shown on the drawings this deflector 9 comprises a pair of oppositely inclined walls intersecting in a longitudinal ridge 10 which is located immediately under the jet openings of the burners. A trough 11 is provided upon each side of the flame deflector 9 and these troughs serve to receive the oil or other inflammable material utilized in starting the burner. Projecting upwardly from opposite ends of the deflector 9 are the standards 12 upon which the generator rests, the said generator being held securely in position by means of the U-bolts 13 which engage perforated ears 90 projecting laterally from the standards.

When starting the burner the necessary quantity of oil or inflammable material is placed in the troughs 11 and ignited, the generator 1 being thereby heated to vaporize the oil or distillate therein. The heat produced by the burner is then sufficient to maintain the generator at the required temperature. As the flame issues from the jet openings 6 it is divided into two sections by means of the ridge 10 and the sections of the flame are deflected laterally in opposite directions. In this manner the burner is prevented from causing the usual roaring noise which is more or less objectionable and the heat is evenly distributed so as to rise and act uniformly upon the generator, thereby maintaining the latter at the required temperature for vaporizing the oil or distillate. It will thus be apparent that the deflector 110 serves the double function of acting as a muffler to prevent noise and also of causing

an even distribution of heat within the fire box.

Having thus described the invention, what is claimed as new is:

- 5 1. In a burner of the character described, the combination of a hollow generator, burners applied to the generator, a deflector comprising oppositely inclined walls which intersect in a ridge, said ridge being disposed immediately opposite the burners and serving to divide the flame issuing therefrom and deflect it laterally in opposite directions, means upon the deflector for supporting the generator, and a trough at the lower portion 10 of each of the inclined walls of the deflector.
- 15 2. In a burner of the character described, the combination of a tubular generator provided upon its lower side with openings,

burner tubes fitted within the openings and provided at their lower ends with jet openings, the upper extremities of the burner tubes being closed by the top of the generator and the upper ends of the tubes being formed with lateral openings for straining the gas, and a deflector comprising oppositely inclined walls intersecting in a ridge which is arranged immediately below the jet openings of the burner tubes and serves to divide the flame issuing from the burner tubes and to deflect it in opposite directions. 25 30

In testimony whereof I affix my signature in presence of two witnesses.

CHARLES H. SCHOFF. [L. s.]
